SEAL ARRANGEMENT

Chauncey G. Suits, Schenectady, N. Y., assignor
to General Electric Company, a corporation of
New York

Application October 17, 1941, Serial No. 415,484

8 Claims. (Cl. 174—18)

This application relates to a seal adapted for use in electrical devices such as transformers, capacitors and switches which contain a dielectric medium at a pressure in excess of several atmospheres.

One of the objects is to provide an improved apparatus for supporting terminal structures and lead-in members.

Another object is to provide an improved means for reducing strain on the terminal structures of apparatus employing differential pressures.

A further object is to provide a structure embodying cooperation between insulated terminal members and the casing containing electrical apparatus in order to eliminate strain on the seal between the insulation of the terminal members and the casing.

While seals between insulating members and the casings of electrical apparatus are well known in the art, when high pressures are used in such apparatus, difficulty has been encountered in satisfactorily protecting these seals. The difference between the pressure in the casing and the outside atmosphere creates strains tending to break the bond with the seal either at the insulator or the casing. While the bond with a casing may be protected by the use of welds and similar methods of uniting metals, that with a vitreous or ceramic insulator is not so easily protected. My invention proposes to protect such a junction by providing additional support at this point.

It is an important feature of the present invention to insulatingly seal an electrical conductor through a wall part having differential pressures on opposite sides of the wall part by hermetically sealing the conductor to a surrounding insulator and providing a supporting member, joined to the wall part to abut a shoulder on the insulator and resist the tendency of the insulator to move under the influence of the large differential pressures acting on it.

While not limited thereto, the invention has been found especially applicable in connection with high pressure switches of the liquid contact type and in the following description will be exemplified by reference to such a switch.

For convenience in illustrating one embodiment of the invention it will be described as applied to a switch of the type disclosed in my co-pending application, S. N. 331,797, filed April 26, 1940, and assigned to the assignee of the present application.

The novel features of my invention will be described with greater particularity in connection

with the accompanying drawing and set forth in the accompanying claims.

In the drawing, Fig. 1 is a longitudinal section of a circuit breaker utilizing the insulator supporting and sealing means of this invention; Fig. 2 is an enlarged sectional view of my improved insulator supporting and sealing means; and Fig. 3 is a perspective view of a part of the circuit breaker illustrated in Fig. 1.

Referring now to Fig. 1, I have illustrated my invention as applied to a circuit breaker 10 employing a liquid contact material, such as mercury, which circuit breaker comprises a pressure-confining casing 11, illustrated as a metallic cylinder so constructed as to withstand relatively high pressures therein. One end of casing 11 is closed by a metallic closure member 12 preferably welded thereto and associated with a suitable threaded terminal 13 through which connections to an external circuit may readily be made. A suitable passage 14 is provided in closure member 12 and is sealed off at 15 as by welding when the circuit breaker has been completely constructed and filled with an appropriate gas (e. g., hydrogen) under pressure. The other end of the pressure confining casing 11 is provided with a terminal 16 which is supported relative to casing 11 by means of the supporting structure of this invention hereinafter to be described.

The terminal 16 supports at its inner extremity, that is, within the casing 11, a complex electrode 21 having two contact portions 22' and 22'' and an intermediate portion 22 which connects the two contact portions (see Fig. 3). During the normal use of the switch the contacts 22' and 22'' engage a quantity of mercury within the casing and in contact with the casing walls. For satisfactory operation the casing should be filled with mercury to the level indicated by the dotted line 20. With this arrangement a complete circuit is provided through the switch between the terminals 13 and 16.

In order to facilitate the circuit-interrupting function of the switch, there is further provided within the switch casing 11 a cup-shaped member 17 of insulating material which is held in abutment with the surface of the electrode contact part 22 by means of a compression spring 18. The cup 17, which is preferably of ceramic material, is provided with a shallow end, remote from the supporting means 18 and closed by a barrier or dam 19. In operation, the switch circuit is broken by tilting the surface so that the dam 19 cuts the surface of the mercury in the manner explained in my above-mentioned co-

pending application. In order additionally to assist the circuit-interrupting operation, there is associated with the electrode structure 21 an arc chute 23 which is provided with ends 24 and 25 and a top cover member 26 adapted to prevent arc gases from escaping the confining space formed by the chute. Also associated with this arc chute is a deionizing means 27 comprising alternate layers of flat and corrugated screen. Furthermore, pressure-confining casing 11 is provided with an insulating liner 28 to prevent any arcing to the walls of the casing 11.

In order to permit the arc which is formed across barrier 19 during the circuit-interrupting operation to be forced into the arc chute 23, magnetic means in the form of a horse-shoe shaped electromagnet 29 (Fig. 3) is provided. This electromagnet is mounted outside the walls of the ceramic cup 17 with its poles adjacent to the barrier 19. A number of turns of the part 22 are wound around the central portion of the electromagnet 29 so that the current flowing to the contact 22" through this part just prior to complete circuit interruption is enabled to develop a magnetic field between the poles of the electromagnet. A suitable insulating means 31 is provided between the structure of the electromagnet 29 and the part 22.

United to the inner extremity of the terminal 16 is a stud 32 having a threaded portion for connection with the electrode 21. A lock nut 33 is used to insure a tight connection between 32 and 21.

As has been previously noted herein, my present invention is primarily concerned with the problem of providing an insulating seal arrangement for the terminal 16 and its associated parts which is adapted to withstand the high pressure assumed to be maintained within the casing 11, and the means employed in this connection may best be understood by reference to the enlarged representation of Fig. 2. As clearly appears in that figure, the terminal 16 extends through a cylindrical glass insulator 35 which, through other agencies shortly to be described, insulatingly supports the terminal from the part of the casing formed as cap 36. The insulator 35 is preferably of cast construction as described in application Serial No. 305,666, filed November 22, 1939 in the name of A. W. Hull and Roy W. Moore, and is in direct sealing contact with a metal sleeve 38 which surrounds the terminal 16. It is the function of this sleeve to permit a slight contraction of the glass of the insulator 35 to occur after the casting procedure without producing an excessive strain such as might be developed if the glass were welded directly to the rigid structure of the terminal 16 itself. In order to make the joint between the terminal 16 and the glass insulator of gas-tight character, there is provided a thimble-like member 37 which is placed over the head of stud 32 and fused into the glass insulator 35, preferably as a part of the original casting operation. The member 37 may be welded to the stud 32 to provide a hermetic joint.

Embedded in and sealed to the mass of the glass insulator 35 at its outer circumference is the inner edge of an annular ring 38 which extends between the insulator and the wall of the metal casing 11 to which it is sealed, for example, by welding as indicated at 43. In order to permit slight expansive movement of the casing to occur without thereby rupturing the seal between the part 38 and the glass insulator 35, the former is

bent transversely into a concave form. Between one of the transversely bent portions of the ring and the adjacent surface of the insulator there is provided an idler ring 39 which is in direct sealing engagement with the glass and which prevents the glass from sealing to the ring 38 in the region subtended by the idler ring.

In order to relieve the strain on the joint between the annular ring 38 and the insulator 35 caused by the difference in pressure which exists between the outside and inside of the casing 11 the glass insulator is provided in accordance with my present invention with a shoulder 40 which cooperates with a correspondingly formed surface on the cap part 36 of the casing. A lead gasket 41 interposed between the shoulder 39 and the aforesaid surface of the cap 36 serves to distribute the stress equally over the conical surface of the insulating member 35. The internal surface of the cap 36 also serves as a supporting abutment for the contour 42 of the member 35. The hermetical closure of the structure is completed by means of the weld 43 between the thin outer edge of the ring 42 and the attenuated edge of the cylindrical container 11. This weld may, because of its location relative to insulator 35, be made without danger of cracking the insulator due to thermal strains. The relationship of the parts is such that the weight of the insulator 35 and of the elements mounted on it are effectively supported by the cap 36 independently of the seal between the part 38 and the insulator thereby relieving the seal of any strain due to this cause.

As a result of the construction described in the foregoing, the sealing arrangement realized is of a character well adapted to withstand differential pressures amounting to many atmospheres while providing at the same time a completely hermetical seal which does not depend upon gasketing to be gas tight. For example, a mercury switch arrangement such as that illustrated may employ an internal filling of a gas such as hydrogen at a pressure of as high as 100 pounds per square inch or more without danger of fracturing the seal or developing gas leakage.

In the construction of seals of the character described it is desired that the sleeve 38, the thimble-like member 37, the annular ring 38, and the idler ring 39 be made of a metal having a coefficient of thermal expansion substantially the same as that of the insulator material. Numerous sealing combinations which meet this requirement are now available inasmuch as glasses have been developed which are adapted to seal satisfactorily with iron or with alloys of iron with nickel or nickel-cobalt.

While I have described a particular embodiment of my invention, it will be obvious to those skilled in the art that various changes and modifications may be made without actually departing from the invention. I, therefore, desire by the appended claims to cover all such changes and modifications as fall within the true spirit and scope of the foregoing disclosure.

What I claim as new and desire to secure by Letters Patent of the United States is:

1. A terminal structure for encased electrical apparatus of the type employing pressures differing substantially from atmospheric comprising an insulator having a shoulder portion, a metal ring having one edge embedded in said insulator and connected to a part of the apparatus casing to provide a seal for said terminal structure, and another part of the casing engag-

ing said shoulder portion and adapted to absorb mechanical stresses attributable to said pressure differential.

2. A terminal structure for encased electrical apparatus subjected to relatively high pressures comprising an insulator, a shoulder portion on said insulator, a metal ring having its inner edge embedded in said insulator adjacent said shoulder and connected to a portion of the apparatus casing to form a seal, and a further portion of said casing engaging both said shoulder and said metal ring to form a support therefor.

3. A terminal structure for encased electrical apparatus subjected to relatively large pressures, comprising a lead-in conductor for said apparatus, an insulator surrounding said conductor and sealed thereto, a shoulder on said insulator, a metal expansion ring embedded in said insulator adjacent said shoulder and sealed to a part of the casing for said apparatus, a portion of said metal ring conforming to one contour of said shoulder, an idler ring disposed between the shoulder and the metal ring, and another part of said casing abutting another contour of said shoulder and a second portion of the metal ring to provide a support for both said metal ring and said shoulder.

4. A terminal structure for encased electrical apparatus of the type employing pressures differing substantially from atmospheric comprising an insulator having a shoulder portion, a metal ring having one edge embedded in said insulator and connected to a part of the casing to provide a seal for said terminal structure, and another part of the casing engaging said shoulder portion and adapted to absorb mechanical stresses attributable to said pressure differential, and a deformable gasket interposed between said shoulder and said member to equalize the stresses on said shoulder.

5. An arrangement for insulatingly sealing an electrical conductor through a wall part having differential pressures on opposite sides of the wall part, said arrangement comprising an insulator surrounding and hermetically joined to the said conductor, a metal ring having its inner edge sealed into the outer portion of the insulator and disposed on the side of said wall

part exposed to the greater of said differential pressures, a shoulder provided on said insulator adjacent to the region of its union with said metal ring, and a surface on said wall part abutting said shoulder and an unembedded portion of said ring for resisting the tendency of said insulator and ring to move or become deformed under the influence of said differential pressures.

6. A glass-to-metal seal for joining an insulator to a casing comprising, a shoulder on said insulator, a metal expansion ring partially embedded in said insulator adjacent said shoulder and sealed to said casing, a portion of said metal ring conforming to one contour of said shoulder, an idler ring disposed between the shoulder and the metal ring, and a member abutting another contour of said shoulder and a second portion of the metal ring and joined to said casing to provide a support for both said metal ring and said shoulder.

7. A glass-to-metal seal for joining an insulator to a wall comprising, a shoulder on said insulator, a metal expansion ring having its inner edge embedded in said insulator adjacent said shoulder and its outer edge sealed to said wall, a portion of said metal ring conforming to one contour of said shoulder, and a member abutting another contour of said shoulder and a second portion of the metal ring and joined to said wall to provide a support for both said metal ring and said shoulder.

8. A glass-to-metal seal for joining an insulator to a casing comprising, a shoulder on said insulator, a metal expansion ring partially embedded in said insulator adjacent said shoulder and joined to said casing to form a sealing connection between the casing and the insulator, a portion of said metal ring conforming to one contour of said shoulder, an idler ring disposed between the shoulder and the metal ring, a member abutting another contour of said shoulder and a second portion of the metal ring and joined to said casing to provide a support for both said metal ring and said shoulder, and a gasket located between said shoulder and said member to equalize the stress on said shoulder.

CHAUNCEY G. SUTTS.
